(57) **CLAIM**

The ornamental design for a configurable leverage bit driver handle, as shown and described.

DESCRIPTION

FIG. 1 is a front perspective view of the configurable leverage bit driver handle showing our new design in a stowed condition;

FIG. 2 is a left side elevation view thereof, the right-side elevation view being a mirror image thereof;

FIG. 3 is a top plan view thereof;

FIG. 4 is a front elevation view thereof;

FIG. 5 is a rear elevation view thereof;

FIG. 6 is a bottom plan view thereof;

FIG. 7 is an exploded perspective view thereof;

FIG. 8 is a front perspective view of an outer element of the configurable leverage bit driver handle;

FIG. 9 is a left side elevation view thereof, the right-side elevation view being a mirror image thereof;

FIG. 10 is a top plan view thereof;

FIG. 11 is a front elevation view thereof;

FIG. 12 is a rear elevation view thereof;

FIG. 13 is a bottom plan view thereof;

FIG. 14 is a front perspective view of an inner element of the configurable leverage bit driver handle;

FIG. 15 is a left side elevation view thereof, the right-side elevation view being a mirror image thereof;

FIG. 16 is a top plan view thereof;

FIG. 17 is a front elevation view thereof;

FIG. 18 is a rear elevation view thereof; and,

FIG. 19 is a bottom plan view thereof.

The broken lines in the drawings illustrate a boundary that forms no part of the design.

The dash-dot-dot-dash lines in the drawings illustrate elements of the configurable leverage bit driver handle that form no part of the design.
